UNITED STATES PATENT OFFICE.

EDWARD WESTON, OF NEWARK, NEW JERSEY.

DESIGN FOR A CASE FOR ELECTRICAL MEASURING-INSTRUMENTS.

SPECIFICATION forming part of Design No. 21,446, dated April 5, 1892.

Application filed January 8, 1892. Serial No. 417,411. Term of patent 14 years.

To all whom it may concern:

Be it known that I, EDWARD WESTON, of Newark, Essex county, New Jersey, have invented a new and original Design for Cases of Electrical Measuring-Instruments, of which the following is a specification.

My design consists in the novel configuration of the case of an electrical instrument, substantially as hereinafter described, and as shown in the accompanying drawings.

In said drawings, Figure 1 is a face view of an instrument-case embodying my design, and Fig. 2 is a side view of said case.

Similar letters of reference indicate like parts.

For purposes of convenience in description the case may be considered as in upright position. The upper portion or wall of the periphery A is curved or rounded in the form of a circular arc. From each end of the wall A extend inwardly-inclined walls B. The angles or corners C between the walls A and

B are rounded. Below the walls B the periphery is curved outward, as at D. The portion of the periphery E extending between the portions D is circular. The front wall F of the case is flat. The rear wall G of the case above the part D is also flat and parallel to the wall F. The rear wall H of the case below the part D is flat and parallel to the wall F. The depth of the case between the walls F and H is greater than its depth between the walls F and G. Between the wall H and the wall G there is a wall I, which is in continuation of the circular periphery E. In the front wall H may appear an opening J.

I claim—

The design for the case of an electrical measuring-instrument, substantially as herein shown and described.

EDWARD WESTON.
